UNITED STATES PATENT OFFICE.

ERIK ARTUR FAGERLUND, OF STOCKHOLM, SWEDEN.

ELECTRIC-CIRCUIT BREAKER AND THE LIKE.

1,088,268.

Specification of Letters Patent. Patented Feb. 24, 1914.

Application filed April 22, 1912. Serial No. 892,442.

To all whom it may concern:

Be it known that I, ERIK ARTUR FAGERLUND, a subject of the King of Sweden and a citizen of Sweden, residing at 4 Bleck-tornsgränd, Stockholm, in the Kingdom of Sweden, have invented certain new and useful Improvements in Electric-Circuit Breakers and the like, of which the following is a specification.

10 My present invention relates to such circuit breakers, time switches or similar devices, in which a movable body has a reciprocating motion in a pipe, containing a liquid. In such instruments claimed in my 15 applications Serial Nos. 637,155, filed July 6th, 1911, and 655,790, filed October 20th, 1911, the movable body forms an armature or core, surrounded by a coil, passed by the current to be broken. The upward motion 20 of the core is effected by a current through the said coil; the downward motion, on the contrary, is effected by gravity, the current through the coil being on said downward motion broken. The breaking and closing 25 of the current through the coil is effected by means of a contact device being magnetically operated by the core in its lower end position.

My present invention has for its object to 30 arrange the instrument in such a way as to be used as an automatically operating time switch or circuit breaker, especially an instrument of the kind where lamp circuits are intermittently closed and opened. This 35 is not practicable with the inventions described in my applications above mentioned.

According to the present invention the contact device is operated by means of a magnetic field set up by a permanent magnet 40 or by a separate current from an electric source completely separated from the source delivering the current through the coil.

In the accompanying drawings: Figure 1 represents a side view, partly in vertical 45 section, of the devices embodying my invention; Fig. 2, a top plan view of the same, the casing being sectioned; Fig. 3, an elevation of such devices looking from right to left at right angles to Fig. 1; Fig. 4, a bottom plan view of such devices, the casing being sectioned; Fig. 5, a view of a modification, which arranges the electromagnetic coil externally in lateral proximity to tube *c*, this magnetic coil, the tube *c* and the solenoid 50 *b* being shown in elevation; and Fig. 6 represents a view similar to Fig. 5 illustrating a modification having a permanent magnet instead of the temporary magnet above mentioned.

a designates a core movably arranged in the solenoid *b*. In order to obtain a quick movement upward but a slow movement downward of the core, this armature is arranged in a tube *c* of glass or metal containing a liquid, for instance oil, petroleum, glycerin or the like. The core is further provided with a bore *d* provided with a valve, said valve opening at the movement upward, but being entirely or partly closed at the movement downward. The rapidity of this movement downward of the core *a* is governed by the leaking through the interspace between the core and the wall of the tube or through the valve. The armature *a* is surrounded by an additional coil *f* which is excited by a current from the separate source of electricity *s*, said coil *f* being connected with *s* by means of the circuits *l'* and *l*. The current through the solenoid *b* is brought up by means of the circuits *l* and *l'*, the former of which is connected with the negative supply circuit wire *l*. The said wire *l*, however, ends in a contact device of the following construction: A plate-form armature *h* arranged in proximity to said tube, and regulated in its throw by screws *i* which are adjustable through it and arranged for contact with said tube or some other fixed part, is located in close proximity to said tube so that it may be sufficiently attracted by said core on the descent of the latter, to draw it over toward said tube as far as allowed by said screws, notwithstanding the resistance of spring *m* which normally holds it back out of action. This plate-form armature *h* is provided at its edge away from said tube with a pair of pivots extending upward and downward through fixed bearings to allow the movement of partial revolution of said armature toward or from said tube and core. The lower pivot *g* of this plate is extended downward and provided (as best shown in Figs. 4 and 5) with a plate-form contact *r*, always occupying the same vertical plane with armature *h* and of course turning with it and said pivot pin. When said armature is drawn toward said core the said contact is brought against a contact screw *k* adjustable through a fixed bracket corresponding to the adjustment of screws *i*, so that as the parts *h* and *r* move together the contact *r* will

reach the screw *k* when the screws *i* reach the tube *c*. The circuit wire *l⁶* is connected with the contact *r* and the circuit wire *l⁹* with the adjustable contact *k*, the latter being connected with the positive circuit wire *l⁴* of the solenoid actuating circuit. In the circuit, on the side of the wire *l³* or *l⁴*, the lamps, motors or similar electrical devices are inserted.

10 The operation is the following: The core *a* executes its movement downward in the position of the different parts shown on the drawing, said movement being moderated by the liquid in the tube *c*. The coil *f* 15 traversed by the current from the source *s*, sets up a magnetic field, which traverses the core *a*. When this core has descended in the tube *c*, the contact armature *h* is attracted, the current path *i³—l⁵—b—l⁶—r—l⁹—l⁴* being thereby closed by the contacts *r* and *k*. It is obvious that this closing 20 of circuit appears at a position of the core *a* which is determined by the intensity of the current in the coil *f*; as however said current is approximately constant, the armature *h* will be attracted by *a* when said core 25 has reached a certain end position. As soon as the said closing of circuit has taken place at which the solenoid *b* is excited, the core *a* is directly attracted and quickly 30 brought upward on account of the opening of the valve *e*. During the movement upward of the core *a* the contact *k—r* is interrupted, so that the core immediately 35 starts its movement downward, whereupon the course described again takes place.

The embodiment can be modified in many ways. It is especially to be observed that the electro-magnetic coil *f* (Fig. 5) or an 40 equivalent permanent magnet *t*, (Fig. 6) may be arranged on the side of the tube *c* suitably opposite to the armature *h*. It will create a magnetic field through the lower part of said core in the lowest position of the latter. The coil *f* may besides be entirely dispensed with, if the contact armature *h* consists of a permanent magnet or is 45 arranged in proximity to such a magnet, *t*, which may be arranged near the side of 50 pipe *c* at a point opposite to said armature *h*, as shown in Fig. 6. It is essential only that the core *a* in its lower end position is passed by a magnetic field set up by a permanent magnet or by a current from a separate 55 source of electricity.

If it be desired that the upward and downward motion of the core *a* be equal, the valve *e* may be omitted.

Having now fully described my invention,

what I claim and desire to protect by Letters Patent is:—

1. In an electric circuit breaker, in combination, a tube containing a liquid, a core in said tube arranged to descend by gravity against the resistance of said liquid, a solenoid surrounding the tube and operating, when energized, to draw up the core and a magnet independent of said solenoid and its circuit and arranged in close proximity to the lower part of said core when in its lowest position, an armature attracted by said core when the latter is magnetized by said magnet, and a circuit through said solenoid closed by such movement of said armature substantially as set forth. 75

2. In an electric circuit breaker, in combination, a tube containing a liquid, a core in said tube, a solenoid surrounding the tube and a permanent magnet arranged in close proximity to the lower part of the tube. 80

3. In an electric circuit breaker, in combination, a tube containing a liquid, a core in said tube, a solenoid surrounding the tube and a permanent, movable magnet arranged in close proximity to the lower part 85 of the tube.

4. In an electric circuit-breaker, in combination, a solenoid, a core descending by gravity through said solenoid, a mechanical device resisting the descent of said core, a magnet arranged to provide a magnetic field through a part of said core as the latter reaches its lowest position, an armature arranged to be attracted by said core when thus magnetized, a contact arranged to close 95 circuit with said armature when the latter is thus attracted, and conductors making circuit through said armature and contact and said solenoid substantially as set forth. 95

5. In combination with a solenoid and a movable armature and contact closing circuit through said solenoid, a core arranged to descend by gravity through said solenoid to a position where its lower end is in proximity to said armature, and a magnet arranged in proximity to the lowest position of the lower part of said core for establishing a magnetic field through the same in order that said core may attract said armature, thereby closing the circuit through the 105 solenoid and drawing up the core again. 110

In testimony whereof I have affixed my signature in presence of two witnesses.
